UNITED STATES PATENT OFFICE.

ALFRED C. SCHMOHL, OF BEAVER FALLS, PENNSYLVANIA, ASSIGNOR, BY MESNE ASSIGNMENTS, TO PRESSED STEEL CAR COMPANY, OF PITTSBURGH, PENNSYLVANIA, A CORPORATION OF NEW JERSEY.

STAKE POCKET.

Application filed October 20, 1927. Serial No. 227,432.

My invention relates to stake pockets for securing stakes to cars and more particularly to that type in which is embodied a swinging door to the pocket, said door being capable of being lifted vertically and swung to one side when opened and not requiring any additional locking means for holding the door when in a closed position.

An object of the invention is to provide a stake pocket with a door which can be easily opened and swung to one side.

Another object of the invention is to provide a hinge for such door which will not become easily damaged and is not liable to bind so as to prevent the opening of such a door.

Another object of the invention is to provide a construction which, upon the opening of the door, will so position the door so that it will be in locking position and will lock automatically when closed.

Referring to the drawings, Fig. 1 is a plan view of the stake pocket and door, attached to a portion of a car; Fig. 2 is an elevational view of the stake pocket and door; Fig. 3 is an elevation of the stake pocket with the door in tilted position before being swung open; Fig. 4 is an elevation of the stake pocket with the door in opened position.

Referring now in detail to the drawings, reference character 1 indicates a portion of a car to which the stake pocket casting 2 is secured; reference character 3 indicates the vertically tilting and transversely swinging door attached thereto. Reference character 4 indicates the rotatable butt portion of the door hinge, comprising a head 5 and a shaft portion 6. The shaft portion 6 is contained in the side 7 of the stake pocket and is secured by means of a nut 8 to a rib 9 of the stake pocket side wall. Encircling the shaft 6 intermediate the rib 9 and the head 5 is a resilient member 10 which is shown in the preferred form as a torsion spring. The head 5 of the rotatable butt portion 4 has an opening 11 formed therein through which the pin member 12 passes to secure the door 3 to the hinge butt. The opposite side 13 of the stake pocket has a slot 14 formed therein which acts as a keeper to engage the portion 15 of the door and hold the door when closed. On the door, adjacent the butt portion of the hinge, is a projecting portion 16 which is adapted to engage the inclined or position-

ing ledge portion 17 of the stake pocket when the door is tilted and swung open.

Assuming the door to be in a closed position, as shown in Fig. 1, and it is desired to open the door and release the car stake, the door 3 is lifted in a vertical direction, by means of the finger 18, causing the door to tilt about the member 4 as a fulcrum until the surface 19 of the door is free of engagement with the keeper 14. The door is now in the position as shown in Fig. 3. With the tilting of the door the projecting portion 16 describes a downward path until it is below the underside 20 of the inclined ledge 17 on the stake pocket. The door is now swung outwardly and away from the car until its assumes the position shown in Fig. 4. As it will be noted from Fig. 4 the door when opened retains the same tilted position as shown in Fig. 3 where the door is tilted to clear the keeper 14. This retention of such a position is caused by the projecting portion 16 of the door, passing under and into contact with the inclined or positioning ledge 17 of the stake pocket when the door is swung open. The resilient member or torsion spring 10 around the shaft 6 of the rotatable butt portion 4 receives an initial twist with the tilting movement of the door and retains this twist throughout all the opening movements of the door. One end portion 21 of the spring passes into the rotatable butt member 4 and the other end 22 is held in a slot 23 of the stake pocket casting.

Upon swinging the door closed, the portion 16 of the door passes out of contact with the inclined ledge 17 of the pocket casting when the door is directly over the keeper 14. The spring 10 being in torsion during the closing movement of the door and released when the member 16 passes out of contact with the inclined ledge, resumes its original position and forces the door down into the keeper slot 14 of the stake pocket. This insures automatic positive locking engagement of the door with its keeper when the door is closed. No additional effort is required of the operator in locking the door other than to swing the door closed. Accidental unlocking or opening of the door is resisted by the spring on the hinge butt and the weight of the door itself.

Having thus described my invention what

I claim as new and desire to secure by Letters Patent is:—

1. A stake pocket having a hinged door adapted to tilt vertically and swing transversely in opening and closing, a butt hinge for said door, the butt of said hinge being adapted to tilt with said door.
2. A stake pocket having a hinged door adapted to tilt vertically and swing transversely in opening and closing, a butt hinge for said door having a rotatable butt portion and a resilient restraining means cooperating with said butt portion.
3. A stake pocket having a hinged door adapted to tilt vertically and swing transversely in opening and closing, a hinge for said door having a rotatable butt, a torsion spring encircling a portion of said butt, one end of said spring engaging the hinge butt and the other end engaging the stake pocket.
4. A stake pocket having a hinged door adapted to tilt vertically and swing transversely in opening and closing, a rotatable butt for said hinge connected to said stake

pocket, a keeper on said pocket adapted to engage a portion of said door, a projecting portion on said door and a positioning ledge on said pocket adapted to engage the projecting portion of said door. 25

5. A stake pocket having a vertical tilting and transversely swinging door, a hinge at one end of the door, a keeper engaging the other end of said door, a rotatable butt for said hinge, a positioning ledge on said pocket and a corresponding engaging portion on said door. 30 35

6. The combination in a stake pocket of a three sided enclosure, a tiltable hinged door for the open side of said enclosure, a keeper for said door, a rotatable butt for said door hinge, a resilient member cooperating with the rotatable hinge butt, an inclined ledge on said stake pocket and a projecting portion on said door engaging said inclined ledge. 40 45

In testimony whereof I affix my signature.

ALFRED C. SCHMOHL.
